CORE DRILL

John F. Bozeman, Lake Charles, La., assignor to
Ace Wire Line Core Drilling Company, a cor-
poration of Texas

Application March 23, 1934, Serial No. 716,990

6 Claims. (Cl. 255—72)

This invention relates generally to deep well drills, and specifically to deep well core drills or sample taking devices.

In the drilling of deep wells it is customary to take cores or samples of the formation through which the drill is passing, and these cores or samples are desired only at certain intervals. As the well may be more than a mile deep, various devices, such as that shown by the patent to 5 Barrett, et al, No. 1,847,424, have been provided whereby a core or sample of the formation may be obtained without the necessity of removing the drill stem from the well, which consumes a great deal of time and is very expensive. In apparatuses of this type, when a core or sample is desired, the core barrel is dropped into the drill stem and descends into an operative position, and after the core or sample has entered the barrel, the core barrel is removed upwardly 10 through the drill stem by means of an overshot or fishing tool attached to the end of a cable, whereupon drilling proceeds until another core is desired, when the operation is repeated.

It has also been found that as drills of the type to which this invention specifically relates are adapted particularly for drilling soft formations, the boring tool of the core barrel, which normally extends below the bit when the core barrel is in place, is so injured when a hard stratum of formation is encountered that the core barrel cannot be withdrawn through the drill stem, and means have heretofore been provided to permit the boring tool to withdraw into the bit when hard formations are encountered to protect it from injury.

This invention has for its general object the provision of certain improvements in the apparatus covered by the said patent to Barrett, et al, No. 1,847,424.

A specific object of the invention is to provide a combination of parts, including a relatively large and strong spring which remains at all times in the drill stem and exerts a downward pressure upon the core barrel, yielding upwardly 40 to permit the boring tool to withdraw into the bit when hard formations are encountered.

Another specific object is to provide a new and improved interengaging means between the core barrel and the drill stem which engage at a substantial distance from the longitudinal axis of the core barrel so that the strain thereupon is reduced and the parts are less liable to injury.

A further specific object is the provision of new and improved means to yieldably hold the 55 interengaging means in engagement and to effect

the positive release thereof upon an upward pull thereon.

Other objects will hereinafter appear.

The preferred embodiment of the invention is illustrated in the accompanying drawing, 5 wherein Fig. 1 is a sectional elevation of the drill stem with the core barrel in place; Fig. 2, a view of the upper part of the apparatus showing the parts in engagement; Fig. 3, a cross section on the line 3—3 of Fig. 2; and Fig. 4, a view showing 10 the relative positions of the parts after they have been disengaged to permit withdrawal of the core barrel.

In the drawing the drill stem is indicated at 1, and the drill bit at 2. The latter may be of the conventional fish tail type, and has a central opening 4 of an internal diameter substantially greater than the external diameter of the core barrel 5. Vertically reciprocal in the drill stem 1 is a drive sleeve 6 held against rotation with 15 respect to the drill stem by the key 7 fitting in the slot 8, and having a spiral lower surface forming a depending abutment 6a. Above the sleeve 6 is a large and strong coil spring 9 to bear 20 upwardly on the shoulder 10 formed by the drill 25 stem coupling 11, and downwardly upon said sleeve.

On the lower end of the core barrel 5 is a boring tool 12, and adjacent said end is a core catcher 13. At the upper end of the core barrel 30 is a relief valve 14. The core catcher 13 operates in the usual manner to permit the core to enter the barrel 5 and to prevent it from falling out of the barrel 5 when the core barrel is elevated. The relief valve 14 functions in the usual manner 35 to permit the escape through the ducts 15 of fluid that would otherwise be trapped in the barrel 5 as the core rises therein, and to prevent the entrance into the barrel 5 of the slush that is pumped through the drill stem. The core 40 barrel 5 is connected by the coupling 16 to a cylinder 17 in which the releasing device 18 is reciprocable. The numeral 19 indicates a fixed pin by which the dog 20 is pivoted. The numeral 21 indicates a movable pin carried by the releasing device 18 and slidable upwardly in the slot 22 of the dog 20. Hooked on the pin 23 and engaging the pin 24 in the releasing device 18 is a spring 25 to bear against the upper surface 26 of the dog 20 when the parts are in the 45 position shown by Fig. 1 for reasons which will hereinafter appear.

The dog 20 is movable through the slot 27 in the cylinder 17 so that its portion 20a may engage underneath the ring 6 and against the abut- 50 55

ment 6a of said ring for the purpose hereinafter referred to.

The drill is used as follows:

During the drilling of soft formations the drill 5 is used without the core barrel in place, muddy water known as slush being pumped downwardly through the drill stem and out through the bore 4 in the bit 2 to keep the bit cool and to remove the cuttings thereof, the said slush rising upwardly in the well about the exterior of the drill stem to the surface of the earth.

When a core or sample of the formation is desired, the drill stem 1 is elevated slightly to remove the bit 2 from the bottom of the well, 15 whereupon the core barrel 5 is dropped into the drill stem. The core barrel 5 will descend until the enlarged portion 5b engages the shoulder 27. The drill stem is then lowered and rotated and the dog 20 will then become engaged under 20 the ring 6 and against the abutment 6a as shown by Fig. 1, the spring 25 serving to yieldably hold the said parts in such engagement. The drill stem thereupon rotates the core barrel 5 through the key 7, sleeve 6 and dog 20 to drive the boring 25 tool 12 below the bit 2 into the formation, slush being meanwhile pumped downwardly through the drill stem. To permit the passage of the slush downwardly between the drill stem 1 and the core barrel 5, the sleeve 6 may be provided 30 with passageways 6b and openings 6c, and the bushing 28 is grooved as indicated at 29. The slush therefore passes through the bore 4 about the core barrel 5. As the boring tool 12 extends below the bit 2, the slush cannot enter the core 35 barrel to contaminate the core.

Now, if a hard stratum of formation is encountered, the boring tool 12 may withdraw up into the bit 2 so that the weight placed upon the drill stem 1 is thereupon carried by the bit 2 and the bit 2 serves to protect the boring tool 12 from injury. Such withdrawal is permitted because the sleeve 6 is slideable upwardly in the drill stem 1 as the spring 9 yields. While the sleeve 6 may move upwardly, the rotation of the 45 boring tool 12 is continued because the key 7 still remains in the groove 8. In other words, while the sleeve 6 may move upwardly in the drill stem 1, it is at all times rotated by the drill stem 1.

50 After the drill has passed through the hard stratum the spring 9 thereupon forces the sleeve 6 downwardly to extend the boring tool 12 to its normal position below the bit 2.

After the core has entered the barrel 5, the 55 barrel may be removed by lowering into the drill stem 1 an overshot 29 on the end of a cable not shown. Overshot 29 will engage the head 30 of the releasing device 18, and when an upward pull is exerted on the cable, the releasing device 60 18 will be moved upwardly in the cylinder 17. Because of the angle between the surface 26 of the dog 20 and the adjacent wall of the slot 22, the tension of the spring 25 will be relieved so that the spring 25 will no longer urge the dog 65 20 outwardly. Pin 21, carried by the releasing device 18, will then continue to move upwardly in the slot 22 pulling the dog 20 inwardly out of engagement with the ring 6. The core barrel will then be free for upward movement through 70 the drill stem.

The various advantages of the above described improvements will be apparent to those skilled in the art. Of these advantages, the following may be mentioned:

75 The spring 9 is a strong, relatively, large, spring

adapted to exert any desired downward pressure on the boring tool 12, and to withstand severe strain. This size is made possible by leaving the spring 9 in the drill stem. If it were carried by the core barrel, it would necessarily have to be small to permit it to pass through the drill stem. 5

The key 7 is substantially remote from the longitudinal axis of the core barrel 5, so that the strain thereon is relatively small. This reduces friction between key 7 and the walls of the slot 8, 10 and consequently reduces wear.

In prior devices, yieldable means have been provided to urge outwardly into their active positions dogs corresponding to the dog 20, but it has been necessary to overcome the resistance 15 of said means in order to move such dogs into their inactive positions. According to my improvement above described, when it is desired to remove the core barrel, an upward pull reduces the tension of the spring 25 so that it does not 20 interfere with the inward movement of the dog 20 by the pin 21.

I claim:

1. A rotary drill of the class described in the specification, embodying the combination with a 25 hollow drill stem, and a bit attached to the lower end thereof and having a central bore; of a core barrel; a boring tool on the lower end of said core barrel; said drill stem having a shoulder therein; a sleeve vertically movable in said drill 30 stem below said shoulder, and keyed against rotation in said drill stem and having a depending abutment; a spring in said drill stem between said sleeve and said shoulder; a dog pivotally carried by said core barrel and having an angular slot 35 therein; a releasing device movable with respect to said dog and having a pin extending through said slot and yieldable means bearing against said dog to yieldably hold it in its active position; said core barrel being insertable downwardly in said drill stem and bit bore into an operative position and said dog being movable underneath said sleeve and against said abutment when said barrel is in said position, and said boring tool being normally below said bit 40 when said barrel is in said position; said spring serving to exert a downward pressure on said core barrel and to yield upwardly to permit said boring tool to withdraw up into said bit when hard formations are encountered; said core barrel being removable upwardly through said drill stem by an upward pull on said releasing device; said releasing device, pin and yieldable means being so associated with said dog that upon such upward movement the tension of said yieldable 45 means is relieved and said pin moves said dog into its inactive position; said core barrel having a core catcher adjacent its lower end and a relief valve adjacent its upper end; and said elements 50 being so constructed as to provide a fluid passageway to permit slush to be pumped downwardly through said drill stem and bit during coring operations.

2. In a rotary drill of the class described in the specification, the combination of a drill stem and a core barrel, of means between said drill stem and core barrel to releasably hold said core barrel in said drill stem, said means including interengaging elements carried by said core barrel 55 and by said drill stem, yieldable means to urge said core barrel element into engagement with said drill stem element, and a releasing device to disengage said elements when an upward pull is exerted on said device, said yieldable means be- 60

75

ing operatively associated with said releasing device and being moved to relieve its tension when an upward pull is exerted on said device.

3. A rotary drill of the class described in the specification, including a drill stem having a bit attached to the lower end thereof, a core barrel in said stem, and having a boring tool attached to the lower end thereof and normally extending below said bit, interengaging elements carried by said core barrel and drill stem, yieldable means to urge said core barrel element into engagement with said drill stem element, and a releasing device 10 slidable with respect to said core barrel and forming a support for said yieldable means, said releasing device being adapted upon upward movement with respect to said core barrel to first move said yieldable means away from said core barrel element and then to move said core barrel element out of engagement with said drill 15 stem element.

4. In a rotary drill of the class described, a drill stem having a bit attached to its lower end and a core barrel insertable therein and removable therefrom and having a boring tool to normally extend below the bit during coring operations, means carried by said core barrel adapted to engage a portion of said drill stem 20 to prevent upward movement of said core barrel with respect to said drill stem, resilient means for urging said first mentioned means into latching position with respect to said drill stem, and means 25 slidable with respect to said core barrel and adapted upon upward movement to first relieve the tension of said resilient means against said first mentioned means and then to retract said mentioned means to unlatched position.

5. A rotary drill of the class described, includ-

ing a drill stem having a bit attached to the lower end thereof, a core barrel in said stem, and having a boring tool attached to the lower end thereof and normally extending below said bit, interengaging elements carried by said core 5 barrel and drill stem, yieldable means to urge said core barrel element into engagement with said drill stem element, and a releasing device slidable with respect to said core barrel and forming a support for said yieldable means, said 10 releasing device being adapted upon upward movement with respect to said core barrel to first move said yieldable means away from said core barrel element and then to move said core barrel element out of engagement with said drill 15 stem element.

6. In a rotary drill of the class described the combination of the drill stem and a core barrel, a latch on said core barrel adapted to engage said drill stem, a releasing device on said core 20 barrel adapted to receive a tool for removing said core barrel from the drill stem, means connecting said releasing device to said latch to disengage said latch from the drill stem upon upward movement of said releasing device with 25 respect to the core barrel and a resilient member carried by said releasing device and engaging said latch when said releasing device is in its lower position to urge said latch into engagement with the drill stem, said resilient 30 means being movable away from said latch by the upward movement of said releasing device.

JOHN F. BOZEMAN.
